UNITED STATES PATENT OFFICE.

HORACE O. CLARK, OF WAUKEGAN, ILLINOIS.

CHAIN CONNECTOR.

Application filed April 13, 1921. Serial No. 460,897.

To all whom it may concern:

Be it known that I, HORACE O. CLARK, a citizen of the United States, residing at Waukegan, in the county of Lake and State 5 of Illinois, have invented a new and useful Chain Connector, of which the following is a specification.

This invention aims to provide a simple but effective means whereby the links of a chain may be held together securely but releasably.

Within the scope of what is claimed, a mechanic may work changes in the structure shown and described, without departing 15 from the spirit of the invention.

In the drawings:—Figure 1 shows in elevation, one member of the connector; Figure 2 is a side elevation of the complete connector, sectioned links being assembled 20 therewith.

The link forming the subject matter of this application comprises two members 1 disposed side by side, each member having spaced openings 2 connected by a slot 3 of 25 less width than the diameter of either opening, the slot defining an interior lug 4 disposed between the openings, each member having a lateral mouth 5 disposed opposite to the lug and communicating with the slot, the lug of one member extending across the mouth of the other member and constituting 30 a closure therefor, each member being provided with a tongue 6 projecting from the

lug of said member, and extended into the mouth of said member.

The links of a chain are shown at 8 and 35 are engaged in the openings 2. It will be clear that the links may be assembled with the connector, by way of the mouths 5, and when the members 1 are in the positions 40 of Figure 2, the links will be held securely but releasably by the connector. The links 8 need not be of the solid form shown in Figure 2, since it is possible to make up a chain composed wholly or in part by connectors of the sort described.

I claim:—

A link comprising two members disposed 50 side by side, each member having spaced openings connected by a slot of less width than the diameter of either opening, the slot defining an interior lug disposed between the openings, each member having a lateral mouth disposed opposite to the lug and communicating with the slot, the lug 55 of each member extending across the mouth of the other member and constituting a closure therefor, each member being provided with a tongue, projecting from the lug of said member, and extended into the 60 mouth of said member.

In testimony that I claim the foregoing as my own, I have hereto affixed my signature.

HORACE O. CLARK.
